UNITED STATES PATENT OFFICE

HENRY W. ROUNTREE, OF RICHMOND, VIRGINIA, ASSIGNOR OF ONE-HALF TO HENRY W. COTTRELL, OF RICHMOND, VIRGINIA.

TRUNK.

No. 825,556.

Specification of Letters Patent.

Patented July 10, 1906.

Application filed December 20, 1905. Serial No. 292,600.

To all whom it may concern:

Be it known that I, HENRY W. ROUNTREE, a citizen of the United States, residing at Richmond, in the county of Henrico and State of Virginia, have invented certain new and useful Improvements in Trunks; and I do hereby declare the following to be a full, clear, and exact description of the invention, such as will enable others skilled in the art to 10 which it appertains to make and use the same, reference being had to the accompanying drawings, and to letters and figures of reference marked thereon, which form a part of this specification.

15 My invention relates to trunks, and more particularly to that class of trunks known as "wardrobe-trunks," in which clothes can be hung on the usual clothes-hangers and such clothes be held securely in extended position, 20 and has for its object the provision of resilient means whereby the clothes on the hangers will be held tightly in their compartment without being rumpled or jammed toward one end during the handling of the trunk irrespective of the number of garments in the 25 wardrobe-compartment, together with details of construction to be hereinafter described and claimed.

Referring to the drawings, in which like 30 parts are similarly designated, Figure 1 is a perspective view of the open trunk. Fig. 2 is a transverse central section. Fig. 3 is a transverse section showing a modified structure.

35 The trunk is composed of two box-like portions hinged together, one being shown as a bureau-section 4 and the other as the wardrobe-section 5. The bureau-section 4 is provided with a number of drawers 6, supported 40 on small metallic angles 7 and held in closed position by any suitable fastenings 8, here shown as sliding bolts. At the upper end of this section is a space 9, having at each side compartments 10, or it may be smaller 45 drawers. On the front of the drawers 6 or on some or all of them are compressors or boards 11, projected forward from the face of the drawers by means of coil or spiral springs 12 or 12^a, and these springs are limited in their 50 outward movement or extension by flexible strips 13 of fabric or leather, or they may be entirely incased by a boxing, as shown at 13^a. On the fronts of the compressors 11 are placed the drawer-pulls 14; but these may readily be

omitted and the drawer pulled out by taking hold of the board 11. For the purpose of illustration I have shown the lowermost drawer without a compressor in order to be able to place a knockdown or collapsible box 15 in the end of the wardrobe-section 5.

At the top of the wardrobe-section is a rod 16, supported by means of a yoke 17, and on this rod are hung the clothes-hangers 18 with the garments 19 on them. The hooks of the clothes-hangers 18 are placed on rod 16 in front of a coil or other suitable spring 20, and in front of the garments and hangers is usually hung a follower 21, formed as a grid and having a suspending-hook 22. The drawer-pulls pass between the bars of the grid.

70 The collapsible box 15 I have shown for the sake of clearness as composed of four sides, the one, *a*, glued or otherwise secured to the back of the wardrobe-section, the one, *b*, to the bottom of the wardrobe-section, and the other two sides *c* and *d* free. The ends of the box are formed by the side walls of the wardrobe-section. The sides of the box can be conveniently made of pasteboard covered with buckram. The box when ready for use, 80 as shown in dotted lines, Fig. 2, has the edge of the lid or side *d* resting on the edge of the back *a*, as shown, and the lid or side *d* carries a hook 23, taking into an eye 24.

In order to prevent the front of the box 85 (the side *c*) from being displaced or bulged out, I use any suitable limiting devices and have shown this as a simple cleat 25, fastened to the sides of the wardrobe-section, one at each end of the box. The box is shown in 90 full lines, Fig. 2, in collapsed position. This box is located at the bottom of the wardrobe-section and can be collapsed when not in use or when it is desired to utilize the full length 95 of the wardrobe-section for very long suits or garments.

The operation is as follows: One or several suits of clothes or garments by means of their hangers are hung on rod 16 in front of spring 20. The follower 21 may or may 100 not be hung in front of the hangers, as shown in Fig. 1. The trunk can then be closed; the front end of yoke 17 and rod 16 will enter the recess 9, and the compressors 11 press on frame 21, forcing it against the garments to 105 compress them, the hooks on the hangers being forced back to compress the spring 20. The several compressors 11 will accommo-

date themselves automatically to varying thicknesses, as shown in Fig. 2, their object being to exert sufficient pressure on the garments to hold them extended in the wardrobe-section. When the trunk is opened, all of the hangers will be projected forward by spring 20, so that the follower-grid and the separate hangers can be readily removed. On one end of the trunk (the top of the wardrobe-section) is a rigid hollow pipe-like handle 27, whose ends are threaded and have flanged sockets 28 screwed on them, which are in turn secured to the trunk. This prevents the trunk from being set up on the wrong end. In case of need I also provide diagonal and transverse straps 29 to hold the garments together and gather in their loose or projecting parts.

Instead of making the collapsible box as described I may dispense with the sides *a* and *b*, securing the front *c* directly to the bottom of the wardrobe-section and letting the lid or side *d* rest on a cleat *d'*, secured to the back of the wardrobe-section, as shown in Fig. 3.

It will be obvious that in order to increase the capacity of the wardrobe-section the drawers in the bureau-section may be omitted and the springs 12 and 12^a secured directly to the back of this section and that when a sufficient number of compressing members 11 are used the follower-grid may be entirely dispensed with. Such an arrangement is shown in Fig. 3, where the springs 112 and 112^a are secured to the lid or coöperating section 4 instead of to the drawer-fronts. In this figure I have omitted the follower and shown two coat-hangers therein, one supporting a long suit and the other a short coat, the compressors 11 accommodating themselves to the unequal thickness automatically.

I claim—

1. The combination with a trunk having the wardrobe-section; of compressors to automatically compress the garments in the wardrobe-section and automatically compensate for unequal thicknesses upon the closing of the trunk.

2. The combination with a trunk having the wardrobe-section; of a coöperating section and yielding means therein to compress and so hold the garments in the wardrobe-section by the closing of the trunk, said means automatically compensating for unequal thicknesses of the garments.

3. The combination with a trunk having a support and a clothes-hanger thereon; of means to automatically move the hangers forward along the support when the trunk is opened.

4. The combination with a trunk having a support and a clothes-hanger thereon; of a spring to automatically move the hangers forward along the support when the trunk is opened.

5. The combination with a trunk having clothes-hangers and a support therefor, and a device to automatically move the hangers forward in one section of the trunk; of means in another section of the trunk to compress the garments on said hangers, and said device, when the trunk is closed.

6. The combination with one of the trunk-sections; of a knockdown folding compartment some of the walls of which are in common with the walls of the section, and when folded form an extension of said section.

7. The combination with a trunk having two sections; of a compartment having a front and top capable of being folded to form an extension of one of said sections.

8. The combination with a trunk having a wardrobe-section; of a compressing member, a coil-spring to project the compressing member and flexible means to limit the projection of the compressing member.

9. The combination with a trunk having a wardrobe-section; of compressing members, coil-springs to project the compressing members and a flexible boxing for said compressing members.

10. The combination with a trunk having a wardrobe-section; of a bureau-section having drawers therein and resilient compressing members on the front of the drawers.

11. The combination with a trunk having a wardrobe-section, clothes-hangers and their support therein, and means to project the hangers forward along the support when the trunk is opened; of a bureau-section, drawers therein, resilient compressing members on the drawer-fronts to compress and so hold the clothes in the wardrobe-section when the trunk is closed, and a flexible boxing for said members.

12. In a trunk, means to prevent the trunk from being stood on one of its ends, comprising a bent pipe, threaded on its ends and sockets on the threaded portions, said sockets being secured to the trunk.

13. The combination with a trunk having a wardrobe-section; of a rod in and projecting from said section, garment-hangers supported on the rod, a follower hung on the rod in front of the hangers, and means to project the hangers and follower along the rod when the trunk is opened.

14. The combination with a trunk having a wardrobe-section; of means therein to support clothes-hangers, a follower hung on said supporting means, a coöperating section and means therein to engage the follower and yieldingly hold it in the wardrobe-section.

15. The combination with a trunk having a wardrobe-section and a coöperating section; of a compressor in said coöperating section to engage the garments throughout their length in the wardrobe-section and hold them therein when the trunk is closed.

16. The combination with a trunk having

a wardrobe-section and a coöperating section; of a plurality of yielding compressors in said coöperating section to engage the garments in the wardrobe-section and automatically accommodate themselves to unequal thicknesses of said garments in the wardrobe-section.

17. The combination with a trunk-section of a closure for said section and a compressor thereon to automatically compress the clothes into said section when closed, substantially as and for the purpose set forth.

18. The combination with a trunk-section,

of a closure for said section and a yielding compressor on said closure to automatically press the clothes into said section when the trunk is closed, substantially as and for the purposes set forth.

In testimony that I claim the foregoing as my invention I have signed my name in presence of two subscribing witnesses,

HENRY W. ROUNTREE.
